H. L. COLLINS

TANK HEATER

Filed Feb. 7, 1922

Inventor
Harry L. Collins
By *Frank Wilson*
Atty.

UNITED STATES PATENT OFFICE.

HARRY L. COLLINS, OF DELMAR, IOWA.

TANK HEATER.

Application filed February 7, 1922. Serial No. 534,654.

To all whom it may concern:

Be it known that I, HARRY L. COLLINS, a citizen of the United States, residing at Delmar, in the county of Clinton and State 5 of Iowa, have invented certain new and useful Improvements in Tank Heaters, of which the following is a specification.

This invention relates to tank heaters of that class adapted to be installed in water 10 tanks used mainly on farms for watering stock, the purpose being to prevent the water from freezing during the cold months.

The primary object is to provide an improved tank heater embodying certain novel 15 features which permit of its being easily installed in either wood or metal tanks, and which when so installed will serve in a very practical and efficient manner the purposes intended.

Another object is to provide a tank heater 20 of novel construction adapted to be fired through a door at one side of the tank, thus promoting convenience in operation and which is submersed in the tank so as to provide maximum heat radiating surface, thereby 25 promoting economy in maintenance and operation.

Another object resides in the provision of a tank heater and novel means for coupling 30 or securing the heater to either curved or straight walls of both wood and metal tanks, the heater being thus applicable to practically any of the conventional makes of tanks.

Other objects and attendant advantages 35 will be appreciated by those familiar with this art as the invention becomes better understood by reference to the following description when considered in connection with the accompanying drawings, in which—

Figure 1 is a top view of a heater embodying my invention applied to a curved-wall wood tank;

Fig. 2, a side elevation of the construction shown in Fig. 1, showing the coupling member and fire door end of the heater in vertical section;

Fig. 3, a top view showing a modified form of the invention in which the heater proper is cylindrical in cross-section;

Fig. 4, a front view of the tank heater proper shown in Fig. 3; and

Fig. 5, a front section of the front plate and fire door end for the cylindrical type of heater.

In the use of my invention the heater casing may be of different sizes, shapes and

proportions, and in the present application I have illustrated two forms, viz: one in which the casing is square in cross-section and the other round. My invention contemplates the application of either one of these casings or the equivalent, to either a straight or a curved wall water tank. In the first example, the heater casing has a straight side adapted for direct connection to the wall of a straight-side tank whether the latter is of wood or metal. This straight-side heater casing may also be applied to a curved-wall tank by the use of an intermediate casing section or coupling as will be described more fully hereinafter.

The heater is preferably in the form of a horizontally elongated casing designated generally by 16, of any suitable cross-sectional shape and adapted to rest on the bottom of a tank and inclosing a suitable grate. The casing has an open end through which it is fired as explained hereinafter, and is closed at its opposite end except for a flue opening through the top, the flue reaching above the level of the water. The casing is preferably of integral construction, such as a casting.

In Figs. 1 and 2, are shown the application of my invention to a tank having a round upright side wall 37 of wood. In this instance an intermediate casing section or coupling 38 is employed for connecting the heater casing to the tank wall. It will be observed that this heater casing section is open from end to end and has a straight side flange 39 bolted to the flange 22 of the heater casing proper by means of bolts 41, and that it extends through the opening 32' in the tank wall 37 and has a curved flange 42 conforming to the outer curvature of the wall 37 and bolted thereto by means of bolts 43, a suitable packing 40 being interposed between said flange and wall. A curved rear plate 44 is secured by the bolts 43 to the inner side of the wall 37. The opening 32' is sufficiently large for passage of the flange 39 and affords water space entirely around and throughout the length of the casing section 38, thereby effecting a practical insulation between this section and the tank wall. The fire door 45 is in this instance hingedly supported on the flange 42. It will thus be seen that with the use of an additional casing section, the same heater may be applied either to a straight or curved wall tank and to tanks of this class made

either of wood or metal. In other words, my invention contemplates and provides a tank heater proper and means for securing the feed end of the tank heater to the side wall of a tank regardless of the shape of such side wall. To accommodate the differences in shape and the arc of such side walls, an intermediate casing section of the character described is employed.

10. In Figs. 3, 4 and 5, I have illustrated a modified form of the invention, in which the casing section designated generally by 46 is circular in cross-section, but in other respects is similar to the principles disclosed with reference to the heater casing 16. That is, the casing has an annular flange 47 at its open end for attachment to the tank wall and has a flue 48, a suitable leg structure 49 at its closed end, and a grate 51. The front plate 52 is annular to conform to the shape of the flange 47, and a circular door 53 is hingedly supported on the plate 52. This heater may be installed in the same manner as described above with reference to the heater 16; likewise, an annular casing section corresponding to the section 38 may be employed for coupling the heater casing 46 to a curved wall tank.

30. It will be apparent from the foregoing that the tank heater is composed of but very few parts constructed in a very simple and practical manner and permitting application to practically any conventional water tank. By so constructing the tank heater that it is supported in part by the tank wall and is fed through such wall, an arrangement is obtained which promotes low cost in production of the parts, ease and simplicity in installing, and convenience and economy in operation and maintenance.

It is believed that the foregoing conveys a clear understanding to the objects prefaced above, and while I have shown several working embodiments it should be understood that these are merely for purpose of illustration, and considerable change might be made in details of construction without departing from the spirit and scope of the invention as expressed in the appended claims.

I claim:

55. 1. The combination with a water tank having a curved upright side wall, of a heater casing disposed in the tank and having a straight-side feed end, a casing section bolted to said straight-side feed end

of the heater and having a curved-side end bolted to the curved wall of the tank, said wall having an opening therethrough registering with the feed opening in the heater, a front plate supported on the outer face of said tank wall, and a feed door mounted on said front plate for closing the opening in said wall and allowing access to the interior of the heater casing.

2. The combination with a tank having a curved upright side wall, a tank casing adapted to be immersed in the tank and having a straight-side open feed end and a peripheral flange around said end, an open-end coupling casing having a peripheral flange at each end, one of which matches the flange on the heater casing and the other of which is shaped to conform to the curvature of the upright tank wall, a plate on the outer side of said wall shaped to match the curved flange on said coupling casing, bolts for clamping said plate and coupling casing flange to the interposed tank wall and for clamping together the other coupling casing flange and the heater flange, and a fire door supported on said front plate.

3. In combination, a water tank, a side wall of which has an opening therethrough, a heater casing adapted to be supported in the tank, submersed, and having a feed end extending through said opening, means connecting said feed end of the heater casing to the outer side of the tank including bolts passing through the tank wall, and a fire door on the feed end of the casing, the portions of said feed end passing through said opening being spaced inwardly from the wall of said opening providing a water insulation between the heater casing and the surrounding wall of the tank.

4. In combination, a water tank having a curved upright side wall provided with an opening therethrough, a heater casing disposed in the tank and having a straight-side flange at its feed end, a heater casing section having a straight-side flange at one end complementary to said flange on the heater casing, means connecting said flanges, said casing section having a feed end registering with said opening in the tank wall and having at said feed end a curved flange complementary to the curved tank wall, bolts passing through said wall and securing said curved flange thereto, and a fire door for the feed end of said casing section.

HARRY L. COLLINS.
